(57) **CLAIM**

The ornamental design for a medical puncture device, as shown and described.

DESCRIPTION

FIG. 1 is a front view of a medical puncture device showing the new design;

FIG. 2 is a rear view thereof;

FIG. 3 is a right side view thereof;

FIG. 4 is a left side view thereof;

FIG. 5 is a top view thereof;

FIG. 6 is a bottom view thereof; and,

FIG. 7 is a perspective view thereof.

The broken lines shown in FIGS. 1-7 illustrate portions of the medical puncture device that form no part of the claimed design.
